BENJAMIN BACON, OF MORRISON, ILLINOIS, ASSIGNOR, BY MESNE ASSIGNMENTS, TO NATIONAL WATCH COMPANY.

Letters Patent No. 96,865, dated November 16, 1869.

IMPROVEMENT IN REVERSIBLE SAFETY-PINION FOR WATCHES.

The Schedule referred to in these Letters Patent and making part of the same.

To all persons to whom these presents may come:

Be it known that I, BENJAMIN BACON, of Morrison, in the county of Whitesides, and State of Illinois, have invented a new and useful Improvement in Watches; and I do hereby declare the same to be fully described in the following specification, and represented in the accompanying drawings, of which—

Figure 1 is a top view, and

Figure 2, a longitudinal section of a pinion, with its gear and arbor provided with my invention, the purpose of which is to enable the pinion to revolve backward freely on its arbor, when breakage of the main-spring of the barrel of a watch may take place, the object being to prevent injury to the train, which would otherwise be likely to happen.

In the drawings—

A denotes the pinion, which engages with the gear of the barrel in which the main-spring of the works of a watch is situated.

B is the arbor of such pinion, and the gear C, to be revolved by such pinion.

The pinion is to revolve freely on the arbor, but is to be coupled with a nut, D, screwed on the arbor, as shown at s, and against the pinion, the coupling being a stud or pin, a, extended from the pinion into a corresponding notch, b, made in the nut. A ratchet and pawl may be substituted for the pin and notch, or there may be other modes of coupling the pinion and nut, when they are in separate pieces.

When the pinion is turned in one direction on the shaft, it will turn the nut so as to screw it toward the pinion, and force the latter against the gear, so as to cause the pressure and friction against the gear to cause the said gear to revolve with the pinion; but when the main-spring may break, and what is called "back-action" follows, the pinion will be free to revolve on the shaft, and will revolve and unscrew the nut, and will impart no rotary motion to the gear or arbor, thus overcoming all danger of injury to the train by reason of the reaction of the spring, resulting from breakage of it.

This mode of applying the pinion is much better than by securing the pinion on the shaft, or by holding the pinion by friction alone, both of which modes

of applying the pinion are objectionable, as well as uncertain.

Where there is only a nut, it has to be screwed so tight to hold the pinion from turning when the power of the spring is upon it, that there is danger of the back-action, when the spring breaks, of its breaking the pinion before the nut can turn back and loosen the pinion; whereas, with my improvement, the nut being connected with the loose pinion, such nut does not have to be screwed tight at all, but the power of the main-spring screws it up when the power is applied, or the watch wound up. In this case it will be seen that the pinion is perfectly loose, and the least back-action will unscrew the nut and pinion, and the latter will be perfectly loose, but still they are both in their place again when the watch is wound up. This is not so with the nut alone, for when the nut is loosened by the back-action, the pinion remains loose, and the watch has to be taken in pieces, and the nut screwed up again.

Should a person or a watchmaker be not perfectly well posted as to how tight the nut should be screwed up, he may screw it so tight that the back-action will not turn the nut, in which case the nut is of no avail whatever, the pinion then being liable to break by the back-action just as much as if there were no loose pinion. The pinion might as well be fastened to the arbor, as to have a nut that is screwed so tight that it will not turn. With my improvement, the pinion will always turn when there is back-action.

Again, if, under ordinary circumstances, the nut is not screwed tight enough, the pinion will turn around when the watch is being wound up, and will let the spring fly back or run down. This is not so with my invention, for the pinion cannot turn without the nut.

I claim in the train of a watch, the combination and arrangement of the separate nut D, and the coupling, substantially as described, with the pinion A, and the arbor B, its screw and gear C, the whole being to operate as specified.

BENJAMIN BACON.
